UNITED STATES PATENT OFFICE.

JOHN R. MCGIFFERT AND THEODORE H. BLAIR, OF DULUTH, MINNESOTA.

INTERLOCKING SHEAVES AND MEANS FOR OPERATING THE SAME.

1,152,528.

Specification of Letters Patent.

Patented Sept. 7, 1915.

Application filed January 13, 1914. Serial No. 811,797.

To all whom it may concern:

Be it known that we, JOHN R. MCGIFFERT and THEODORE H. BLAIR, citizens of the United States, and residents of Duluth, county of St. Louis, State of Minnesota, have jointly invented a new and useful Improvement in Interlocking Sheaves and Means for Operating the Same, of which the following is a specification, the principle 10 of the invention being herein explained, and the best mode in which we have contemplated applying that principle, so as to distinguish it from other inventions.

The present improvements relating as indicated to interlocking sheaves and means for operating the same are more particularly related and adapted to be used in connection with log skidding machines, although of course the invention is by no means limited to this specific field. In fact the invention may be used whenever it is necessary to permit a lifting and a hauling operation as will be evident from the following description.

25 To the accomplishment of these and related ends said invention then consists of the means hereinafter fully described and particularly pointed out in the claims.

The annexed drawing and the following 30 description set forth in detail certain mechanism embodying the invention, such disclosed means constituting, however, but one of various mechanical forms in which the principle of the invention may be used.

35 Figure 1 is a more or less diagrammatic view in side elevation, showing our invention as applied to a log skidding machine; Fig. 2 is a partial plan view of the same; and Fig. 3 is a section on the line 3—3 in 40 Fig. 2.

In order to clearly point out the improvements which we have made in such mechanism it may first be desirable to briefly outline the construction of the apparatus which 45 has heretofore been used in some cases for lifting and hauling in logs and the like. Referring then to Fig. 1, there is shown a car 1 which may be operated upon a suitable track 2, there being placed upon this car a boom 3 of any convenient construction, which may be maintained in position by any of the usual means, which are not shown in the present views. Upon the boom is mounted a plurality of pulleys or sheaves 4, 5 and 6. 50 Over these three pulleys are passed cables 7,

8 and 9 which are received upon suitable winding-in sheaves or drums 10, 11 and 12 respectively, mounted on the car 1. Over the pulley 4 and the winding drum 10 passes the cable 7 which may be fixed at its outer end to any suitable support, such as a tree, indicated at 13. This cable 7 forms between the pulley 4 and the tree 13 a trackway upon which there is movably mounted a suitable carriage 14 which is of a well-known construction and need not be further described. The carriage 14 is adapted to be moved away from the sheave 4 by means of the receding or 60 outhauling cable 8, such cable having one end attached to the carriage from which it passes over a sheave 15 attached to the tree and then back between rollers 16 in the carriage, from which point it passes down over the sheave 6 and to the winding drum 12. A pulley 17 is attached to the carriage 70 14 and over this pulley passes the cable 8, which may be termed the lifting cable, and which passes over the sheave 5 to the drum 11, which operates to wind in the cable 8, 75 when it is desired to lift the load, which in 80 the present instance is shown as a log 18.

It will be understood that by the term "sheave" as here used, we refer, of course, to any suitable rotative element designed to receive thereover a cable or the like. 85

The mechanism as so far described has been in use for some time and is unsatisfactory in several respects. It will be noticed that upon the winding in of the lifting cable 8 the weight of the load 18 over 90 the pulley 17 will tend to move the carriage 14 to the right on the trackway 7. To prevent this action a sufficient resistance must be applied to the outhauling cable 9 to either maintain the carriage in a stationary position or to permit the same to move slowly 95 to the right. This resistance is secured most conveniently by means of a brake 33 acting upon the drum 12 but the power which must be absorbed by this brake is considerable 100 and it is difficult to provide a practical construction. By means of our present invention we have eliminated this difficulty and have secured a construction which is more convenient to operate, safer, and simpler to 105 control. It will be noticed that the cables 8 and 9, which lead down to the winding drums 11 and 12 respectively, are substantially parallel. We accordingly mount upon the boom 3 a short shaft 20 upon which are 110

mounted two rotating elements, preferably in the form of sheaves 21 and 22, each of which are freely rotatable upon the shaft 20. The lifting cable 8 is passed one or more times around the sheave 22 and the outhauling cable 9 is similarly passed around the sheave 21 but in the opposite direction. The sheave 21 is mounted upon the shaft 20 in lateral contact with a stop in the form of a collar 23. Upon one face of the sheave 21 we provide a concentrically disposed band 24 having converging frictional outer and inner surfaces which are adapted to be engaged by bands 25 similarly mounted on the sheave 22; such bands being spaced from each other and having their adjacent faces diverging, thus adapting them to engage with the band 24 upon movement of the sheave 22 toward the sheave 21. Such movement of the sheave 22 may be secured in various ways but a simple construction for this purposes may be as follows. A portion 26 of the shaft 20 is threaded and adjustably mounted upon this portion 26 is a collar 27 having a radially extending lug 28 engaged by a link 29 which is connected by means of another link 30 to an operating lever 31 which may be maintained in any desired position by means of a pawl and ratchet 32 mounted upon the car.

From the foregoing description the operation of our invention will be easily understood. When the lifting cable 8 is attached to a load and is ready to be wound in, thus lifting the load, it is only necessary to operate the collar 27 by means of the lever 31. This action results in the unlocking of the two sheaves. In operation the outhaul cable 9 is first held in a fixed position by means of a suitable brake 33 on the drum 12, during which time the cable 8 is wound in until the log is raised to the desired position. The sheaves 21 and 22 are then interlocked as has been described, when the cable 8 is wound in thus paying out the cable 9 at the same speed.

By passing the cables 8 and 9 around the sheaves 21 and 22 a number of times the resistance necessary to maintain the carriage 50 14 against too rapid movement to the right is greatly lessened, and with two turns around the sheaves the braking power which must be applied to the drum 12 is cut down to merely a fractional part of what is necessary in the former constructions. We have not here indicated any specific type of brake for the drum 12 but indicate diagrammatically a brake 33 which may, of course, take any desired form.

60 The present device may be conveniently and manually operated by the operator stationed on the car. By the use of our invention much power is saved as when hauling long distances the brake required in the former mechanism would absorb consider-

able power. Furthermore, a much better control may be had of the cables than when they were independently regulated.

The use of the specific type of interlocking sheaves which we have invented is by 70 no means confined to lifting and hauling operations as this feature may be of service in numerous mechanisms.

Other modes of applying the principle of our invention may be employed instead of 75 the one explained, change being made as regards the mechanism herein disclosed, provided the means stated by any of the following claims or the equivalent of such stated means be employed.

We therefore particularly point out and distinctly claim as our invention:—

1. In apparatus of the character described, the combination with a suitable trackway and a carriage movable therealong; of an 85 outhauling cable attached to said carriage; a lifting cable movably supported thereover; two axially alined, freely rotatable elements movable axially into engagement, each of said cables receiving one of said cables thereover; and means adapted to move said elements into such engagement, and to lock the same together, whereby the movement of said outhauling cable is controlled by said lifting cable. 90

2. In apparatus of the character described, the combination with a suitable trackway and a carriage movable therealong; of an 100 outhauling cable attached to said carriage; a lifting cable movably supported thereover; a freely rotatable sheave receiving thereover said lifting cable; a second sheave axially alined with said first-named sheave and movable axially into engagement therewith, said second sheave being also freely 105 rotatable; and means adapted to lock said two sheaves together, whereby the movement of said lifting cable controls the movement of said outhauling cable.

3. In apparatus of the character described, 110 the combination with a suitable trackway and a carriage movable therealong; of an outhauling cable attached to said carriage; a lifting cable movably supported thereover; a shaft; a sheave receiving thereover 115 said lifting cable, said sheave being rotatably mounted on said shaft; a second sheave receiving thereover said outhauling cable, said second sheave being also rotatably mounted on said shaft adjacent to said first-named shaft and being axially movable into engagement with said first-named sheave; and manually operable means adapted to lock said two sheaves together, whereby the 120 movement of said lifting cable controls the 125 movement of said outhauling cable.

4. In apparatus of the character described, the combination with a suitable trackway and a carriage movable therealong; of an 130 outhauling cable attached to said carriage;

- a lifting cable movably supported thereover; a shaft; a sheave receiving thereover said lifting cable, said sheave being rotatably mounted on said shaft, and being provided 5 with a friction surface on one side; a second sheave also rotatably mounted on said shaft and receiving thereover said outhauling cable, said second sheave having a friction surface adjacent such friction surface 10 on said first-named sheave and being axially movable into engagement therewith; and means adapted to move said second sheave into engagement with said first-named sheave.
- 15 5. In apparatus of the character described, the combination with a suitable trackway and a carriage movable therealong; of an outhauling cable attached to said carriage; a lifting cable movably supported thereover; 20 a shaft; a sheave rotatably but non-slidably mounted on said shaft and having a clutch member on one side, said sheave receiving thereon said lifting cable; a second sheave rotatably mounted on said shaft and having 25 a clutch member on one side adapted to engage such member on said first-named sheave upon axial movement of said second sheave, the latter receiving thereover said outhauling cable, and said shaft being threaded adjacent to said second sheave; and means 30 adjustably mounted on such threaded portion of said shaft and adapted when rotated to force said second sheave against said first-named sheave, thereby engaging said members.
- 35 6. In apparatus of the character described, the combination with a suitable trackway and a carriage movable therealong; of an outhauling cable attached to said carriage; 40 a lifting cable movably supported thereover; a winding drum adapted to receive and operate said lifting cable; a second winding drum adapted to receive and operate said outhauling cable; two freely rotatable elements disposed between said drums and said carriage, each of said elements receiving one of said cables thereover; and means adapted to lock said elements together, whereby movement of said lifting 45 50 cable controls the movement of said outhauling cable.
- 55 7. In apparatus of the character described, the combination with a suitable trackway and a carriage movable therealong; of an outhauling cable attached to said carriage; a lifting cable movably supported there-
- over; a winding drum adapted to receive and operate said lifting cable; a second winding drum adapted to receive and operate said outhauling cable; two sheaves disposed between said drums and said carriage, each of said sheaves receiving one of said cables thereover; and means adapted to lock said sheaves together whereby movement of said lifting cable controls the movement of 60 65 said outhauling cable.
8. In apparatus of the character described, the combination with a suitable trackway and a carriage movable therealong; of an outhauling cable attached to said carriage; 70 a lifting cable movably supported thereover; a winding drum adapted to receive and operate said lifting cable; a second winding drum adapted to receive and operate said outhauling cable; a shaft; a sheave 75 receiving said lifting cable thereover and mounted on said shaft; a second sheave receiving said outhauling cable thereover and mounted on said shaft adjacent said first-named sheave; and means adapted to lock 80 said two sheaves together whereby movement of said lifting cable controls the movement of said outhauling cable.
9. In apparatus of the character described, the combination with a trackway and a carriage movable along the same; of an outhauling cable connected to said carriage, passing over a suitable sheave adjacent to one end of the trackway and then passing back parallel to said trackway; a shaft; a 90 sheave rotatably mounted thereon, said sheave receiving said outhauling cable; a winding drum adapted to receive and operate said outhauling cable; braking means on said winding drum tending to prevent 95 movement of the same in a direction to unwind said cable; a suitable sheave mounted on said carriage; a third sheave rotatably mounted on said shaft adjacent said first-named sheave; a lifting cable passing over 100 said second and last-named sheaves; a winding drum adapted to receive and operate said lifting cable; and means adapted to lock together said first-named and said last-named sheaves.

Signed by us, this 5th day of January, 1914.
